UNITED STATES PATENT OFFICE.

GEORGE E. SAUNDERS, OF BURDEN, KANSAS, ASSIGNOR OF ONE-HALF TO
W. T. BEASLEY, OF SAME PLACE.

MECHANICAL POWER.

SPECIFICATION forming part of Letters Patent No. 317,023, dated May 5, 1885.

Application filed December 18, 1884. (No model.)

To all whom it may concern:

Be it known that I, GEORGE E. SAUNDERS, a citizen of the United States, residing at Burden, in the county of Cowley and State of Kansas, have invented new and useful Improvements in Mechanical Powers, of which the following is a specification, reference being had to the accompanying drawings.

My invention relates to mechanical powers; and it consists in the construction and novel arrangement of parts as will be hereinafter fully described, and particularly pointed out in the claims.

In the drawings, Figure 1 is a view in perspective of a mechanical power embodying my improvements, arranged in connection with a derrick, drill-rope, and drill for drilling a well. Fig. 2 is a plan view showing the gate in both full and dotted lines. Fig. 3 is a transverse vertical sectional view on the line $\alpha\alpha$ in Fig. 2; and Fig. 4 is a detail view, showing the rock-shaft and the angle-lever and guide-bails on the arms of said lever. Fig. 5 is a view in perspective of a small pulley and block.

Referring by letter to the accompanying drawings, A and B designate the sills, which are provided with metal strap-loops C and C', one each on opposite sides of the bed-plate D, which latter is let into recesses in the upper faces of said sills and is firmly secured thereto by spikes or stout wooden pins. The strap-loops C and C' are provided in order that stakes may be driven through them into the ground to secure the machine firmly in place when it is in operation.

Near one end of the bed-plate D, I provide a vertical shaft or journal, E, upon which I mount the driving or operating wheel F. The hub F' of the wheel F is made of hard wood, provided with a metal box, F'', to permit lubrication and to prevent wear. The spokes or arms G of the wheel F are made also of wood, and their tenons extend clear into the box in the hub. These spokes G are strongly braced near their outer ends by wooden braces H, and between these braces and the hub they are further strengthened by a metal ring, I, which is secured upon the spokes just inside of the stakes I'. The drill-rope I'' is to be coiled around the outside of the stakes I' when the machine is to be transported from place to

place. The forward faces of the spokes G are slightly rounded off at their outer ends, and these rounded portions are provided with metal wear-plates J. A sweep, K, is secured upon the hub and to two diametrically-opposite spokes of the wheel by metal straps K'. At the other end of the bed-plate from the point of location of the wheel F, I provide a gate-frame, L, in which I pivot a gate, M. 55 This gate M is provided at its front end with a friction-roll, N, which is journaled on a vertical shaft, N', having its bearings in the projecting ends of metal straps N'', secured to the upper and lower edges of the gate M. The 60 gate M is arranged to swing in an open frame, O; but its throw is limited by the posts P at the sides of said frame O.

In the face of the gate M, in the side opposed to the direction in which the wheel rotates, is provided a hook, Q, to which one end of a connecting-rod, R, is engaged.

S designates a derrick, which is erected over the place where the well is to be bored. This derrick S is provided near its lower end with 75 a rock-shaft, T, which has its bearings in the two parallel poles of the derrick quite near the ground. This rock-shaft T is provided with an angle-lever, U, having two arms, Q' Q'', which are strengthened by a brace-rod, U'. 80 At their lower ends the arms of the angle-lever U are provided with pivoted metal bails I' I''. The outer end of the connecting-rod R is attached to the bail I'', and to the bail I' is attached one end of the drill-rope I'', which 85 passes up over the pulley X, and has the drilling-tool attached to its depending end. When the wheel F is rotated by means of the sweep, the projecting end of one of the spokes strikes against the outer end of the gate M and moves 90 it to the position shown in solid lines in Fig. 2. The rod R, which is connected to the gate and to the angular lever U, lowers the upper arm of said lever, and thereby raises the drilling-tool a distance of about two feet. When 95 the end of the spoke passes by the gate and releases it, the gate is drawn back by the gravity of the drilling-tool to the position indicated in dotted lines in Fig. 2. Continued rotation of the wheel causes the drilling-tool to be raised 100 and dropped very rapidly, and thereby causes it to dig the well.

When it is desired to raise the drilling-tool from the well, the rod R is disconnected from the bail I⁴, a pulley, Z, which I have illustrated at Fig. 5, is attached to said bail, and the drill-rope is passed over said pulley and wound upon the stakes I' by rotating the wheel.

Having thus fully described my invention, what I claim as new, and desire to secure by Letters Patent of the United States, is—

1. The combination of the bed, the wheel having projecting spokes and a sweep, and the pivoted gate with the derrick having the rock-shaft and angle-lever, and the connecting-rod 15 for connecting one of the arms of the angular lever to the gate, substantially as described.
2. The combination of the bed, the wheel

having projecting spokes, stakes, or pins I' and a sweep, and the pivoted gate with the derrick, the rock-shaft, and the angular lever 20 U, having bail I⁴, connecting-rod R, that is secured to the gate and that is adapted to be connected to and disconnected from the bail I⁴, and a pulley that is adapted to be hung to said bail when the rod R is disconnected therefrom, for the purpose set forth, substantially as described.

In testimony that I claim the foregoing as my own I have hereto affixed my signature in presence of two witnesses.

GEORGE E. SAUNDERS.
